COVER OPERATED DISPLAY BOX

Melvyn Goldshine, Flushing, N. Y., assignor to
 American Safety Razor Corporation, Brooklyn,
 N. Y., a corporation of Virginia

Application January 10, 1951, Serial No. 205,350

4 Claims. (Cl. 206—45.13)

1

This invention relates to display boxes and has for its principal object the provision of a novel container for small articles such as pocket lighters and jewelry in which the individual articles may be packed and sold and in which means are provided for displaying such articles in an advantageous position while on the store counter.

Another object of the invention is to provide a display container formed with a tray for the article which lies wholly within the box when the latter is closed but which instantaneously and automatically springs to a partially elevated rearwardly inclined position when the box cover is opened, thus displaying the article carried on the tray in a most attractive fashion.

A further object of the invention is to provide an improved display box comprising a body section and a similarly shaped hinged cover section, a display tray and support therefor and wherein both the box and the support have spring means for maintaining the parts both in closed and in open position, thus preventing casual closing of the cover section or sagging of the tray under the weight of the article carried thereby.

In the drawing:

Fig. 1 is a perspective view of a display box embodying the present invention;

Fig. 2 is a perspective view showing the box in open position;

Fig. 3 is a longitudinal section taken through the center of the closed box;

Fig. 4 is a section taken through the box in partially opened position;

Fig. 5 is a section taken through the box when in fully opened position;

Fig. 6 is a transverse section taken on line 6—6 of Fig. 3;

Fig. 7 is a broken section taken on line 7—7 of Fig. 4.

The display box of the present invention includes a body section 10 and a similarly shaped cover section 11 hinged to the body section at 12. Both sections may be made from sheet material such as cardboard with suitable covering or wrapping, metal, or plastic material. In the event of the latter the sheet material may, if desired, be transparent.

A curved spring 13 formed from flat sheet metal may be incorporated in the two-part hinge assembly 14 and which urges the cover section to fully closed or to fully open position. A convenient method of securing the terminals of the spring may comprise forming openings 15 in the hinge elements and bending the terminals to

2

grasp the horizontal edges of the openings as shown at 16.

The display section includes a tray 17 of a width to fit snugly between the side walls 18 of the body section and of a length slightly less than the length of such body section. The tray carries an insert 19 which may be covered with decorative fabric and which is formed with a recess 20 shaped to receive the article to be contained therein, such as a cigarette lighter. Flanges 21 around the margins of the insert engage the side walls of the tray in snug-fit relation.

The tray is automatically moved from closed position, largely in the body section, when the box is in closed position, to its open or displaying position when the cover section is opened, by means of a supporting element which may be formed from a strip of sheet material, of the same width as the tray. This strip comprises a lower section 24 of greater length than the length of the tray, a shorter intermediate section 25 defined along its lower edge by a fold line 26, such section being of lesser height than the combined height of the body and cover sections, and an upper section 27 joined to the intermediate section by a fold line 28.

The lower section 24 is secured to the lower surface of the tray as by means of staples 31 and has an intermediate, transverse fold line 32 disposed closer to fold 26 than to the forward edge of such section. Fold line 32 defines a sub-section 33 of lower section 24 and is of a length greater than intermediate section 25. Slots 30 are formed centrally of section 25 and sub-section 33 substantially equidistant from fold line 26 and the terminals 34 of a curved spring 35, similar to spring 13 are received in such slots. This spring is so formed as to be substantially at rest when the box is closed and section 25 is at right angles to sub-section 33 as shown in Fig. 3. When, however, the box is opened to the position shown in Fig. 5, spring 35 limits the fall of sub-section 33 to a position at an angle substantially 45° to the horizontal. This causes the tray to be held at somewhat the same angle but oppositely disposed.

Because the box of the present invention is usually formed from a wrapped cardboard blank, a similarly wrapped insert 40 is shown as covering the major portion of the lower wall of the body section.

Spring 13 is substantially at rest when the box is closed and is under a considerable bending tension when fully opened and such spring maintains the cover in this open position due to the

fact that the axis 12 of the hinge has passed a center line between the terminals of the spring. Spring 35 is under some bending tension when the tray is in its elevated, inclined position but is influenced only slightly by the weight of the article on the tray.

I claim:

1. A display box comprising a body section, a cover section hinged thereto, a curved spring secured at its terminals above and below the hinge axis to the cover section and the body section, respectively, to maintain the cover section in open position, a tray for holding and displaying an article contained in the box and being of lesser length than the body section, and means for elevating the tray to a rearwardly inclined position with its lower end in the body section when the box is open, such means comprising a strip of flat material having a lower section secured to the tray, an intermediate section of lesser height than the box and disposed adjacent the box wall carrying the hinge, an upper section secured to the cover section, and fold lines at the upper and lower ends of the intermediate section forming hinge elements between the intermediate section and the upper and lower sections, respectively, and a fold line between the ends of the lower section, said fold lines being parallel with the hinge axis, and a curved spring secured at its terminals to the strip above and below the fold line between the intermediate and lower sections of said strip for maintaining the tray in said rearwardly inclined position when the box is open.

2. A display box comprising a body section, a cover section hinged thereto, a tray for holding and displaying an article contained in the box, and means for elevating the tray to a rearwardly inclined position when the box is open, such means comprising an elongated supporting member having a plurality of spaced, transverse hinge elements disposed parallel with the box hinge and dividing the member into a plurality of interconnected hinged sections including a rear and front lower section, the latter being attached to the tray, an intermediate section disposed adjacent the rear of the box and which is generally vertically disposed when the box is closed, and an upper section secured to the cover section, a spring secured at its terminals to the supporting member above and below the hinge element between the upper and the intermediate sections of said member for maintaining the rear lower section in a forwardly inclined position and the tray in said rearwardly inclined position when the box is open.

3. A display box comprising a body section, a cover section hinged thereto at the rear of the box, a tray for holding and displaying an article contained in the box, such tray being of lesser length than the body section and lying largely within said section when the cover section is closed, and means for elevating the tray to a

rearwardly inclined position with its lower front end positioned in the body section to the rear of the front thereof when the box is open, said means comprising a strip of flat material having a lower section attached to the tray, an intermediate section of lesser height than the box and disposed adjacent the rear thereof, an upper section secured to the cover section, and fold lines at the upper and lower ends of the intermediate section and a fold line between the ends of the lower section, said fold lines forming hinge elements and being parallel with the box hinge, a spring secured at its terminals to the cover section and the box section, respectively, above and below the box hinge for maintaining the box in open position, and a spring secured at its terminals to the strip above and below the fold line between the intermediate and lower sections of said strip for maintaining the adjacent part of the lower section in a forwardly inclined position and the tray in said rearwardly inclined position when the box is open.

4. A display box comprising a body section, a similarly shaped cover section hinged thereto along the rear top edge thereof, a tray for holding and displaying an article contained in the box and provided with an insert having an opening shaped to fit the article, such tray being of lesser length than the body section and lying largely within said section with its front end at the front of the box when the cover section is closed, and means for elevating the tray to a rearwardly inclined position with its front end in the body section to the rear of the front of the box when the box is open, said means comprising a strip of flat material having a two-part lower section, an intermediate section of lesser height than the box and disposed adjacent the rear of the box, an upper section secured to the cover section, and fold lines defining such sections and forming hinge elements therebetween which are generally parallel with the box hinge, a curved spring formed from sheet metal secured at its terminals to the cover and box sections above and below the hinge line for maintaining the box in open position, and a similar spring secured at its terminals to the strip above and below the fold line between the intermediate and lower sections of said strip for maintaining the adjacent part of the lower section in a forwardly inclined position when the box is open, the other part thereof being secured to the tray.

MELVYN GOLDSHINE.
